CLAIM

The ornamental design for a terminal, as shown and described.

DESCRIPTION

FIG. 1 is a front, and top and right side perspective view of a terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom and left side perspective view thereof; and,

FIG. 9 is a front, top and right side perspective view showing the terminal fastened to an electrical connector.

The broken lines depict portions of the terminal in which the design is embodied that form no part of the claimed design. The dot-dash lines represent the boundaries of the claimed design that form no part of the claimed design.

The shade lines on the surface of the terminal indicate contour and not surface decoration.
